UNITED STATES PATENT OFFICE

106,381

DESIGN FOR A CAPE

Morris Spector, New York, N. Y.

Application August 25, 1937, Serial No. 71,305

Term of patent 3½ years

To all whom it may concern:

Be it known that I, Morris Spector, a citizen of the United States of America, residing in city of New York, county of New York, and State of New York, have invented a new, original, and ornamental Design for a Cape, of which the following is a specification, reference being had to the accompanying drawing, forming part thereof.

Fig. 1 is a front view of a cape showing my new design.

Fig. 2 is a rear view thereof.

I claim:

The ornamental design for a cape substantially as shown.

MORRIS SPECTOR.
